UNITED STATES PATENT OFFICE.

T. TRASK WOODWARD, OF PANA, ASSIGNOR OF ONE-HALF TO THOMAS H. WINGATE, OF DECATUR, ILLINOIS.

VAPOR-BURNER.

SPECIFICATION forming part of Letters Patent No. 272,998, dated February 27, 1883.

Application filed December 20, 1882. (No model.)

To all whom it may concern:

Be it known that I, T. TRASK WOODWARD, a citizen of the United States, residing at Pana, in the county of Christian and State of Illinois, 5 have invented a new and useful Improvement in Vapor-Burners, of which the following is a specification.

My invention relates to certain new and useful improvements in vapor-burners; and it consists in an elongated combustion-chamber and corresponding cap, provided with a transverse bar to spread the flame, the relative positions of the valve and fluid-tube on opposite sides of the conducting-tube, two jet-orifices controlled 15 by one valve, and the manner of conveying the fluid or gas around three sides of the conducting-tube, thereby forming a powerful generator, especially adapted for heating soldering-irons and tempering small tools, all of which 20 will be hereinafter more fully described, and such features as are believed to be new pointed out in the claims, reference being had to the accompanying drawings, in which—

Figure 1 is a vertical longitudinal section, 25 showing its interior construction entire. Fig. 2 is a top or plan view of the burner with the cap removed. Fig. 3 is a plan view of the inside of the cap, showing the position of the bar for the purpose of spreading the flame.

Similar letters refer to similar parts throughout the several views.

A represents the base and generator; B, the cup formed onto the generator and elongated in shape. C is the fluid-inlet pipe; D, the conducting-tube up through the generator A. d d are fluid or gas canals, which pass on three sides of the conducting-tube, and at a different height from that of the supply and discharge tubes. E represents the valve; e, valve-screw; e', drip-cup, and a a are two separate and distinct jet-orifices controlled by one valve E. These jets are arranged side by side and in relation to the length of the burner-cup. F is the removable cap, provided with a series of 45 jet-orifices. b is a transverse bar, located at the center thereof and on the under side, for the purpose of spreading the flame or dividing the two jets, throwing them to either extremity of the burner. The oblong form of the cup

or burner is designed most especially for use 50 in heating soldering-irons and tempering small tools, as its heat is very intense. Some advantages are gained by the peculiar formation and location of the generator, it being so arranged that its upper half is within the combustion-chamber or cup. The fluid is admitted near its lower end, on one side, and rises 55 up the canal d, passes around one side of the generator, near the conducting-tube D, which is formed up through its center, to the opposite 60 side from that at which it entered, thence down canal d to the valve E. There is a hole drilled up into the lower stem of the valve at e, which is plugged at its lower end by a screw-plug, which may be removed for the purpose 65 of cleaning out the jets with a small wire whenever clogged by sediment or rust. It will be obvious that with this construction of burner, with its powerful generator, all fitters and packing in the pipes are elsewhere entirely 70 dispensed with, as neither is required. The cap F is provided with an inverted rim, f, which fits into the cup. (See Fig. 1.) In this figure the cap is shown slightly elevated above the cup, but when properly adjusted fits down 75 flat on the top of said cup, forming a tight joint and an exceedingly large combustion-chamber.

I am aware that an inverted cone has been used in the top of the cap for the purpose of 80 spreading the flame. This I do not claim, broadly, but in combination with two separate and distinct jets controlled by one valve and arranged under one conducting-tube, as shown.

It will be obvious that by this peculiar construction of burner, and the location of the generator and the fluid-canals almost entirely within the combustion-chamber and constantly enveloped in flame, I obtain a powerful generation, sufficient to supply my double-jet valve 85 90 and produce a perfect combustion without the usual offensive smell of unconsumed gasoline.

Having thus fully described my improvement, what I believe to be new, and desire to secure by Letters Patent, is—

1. In a vapor-burner, the valve E, formed with a pair of jet-orifices located below and adapted to discharge through a single conducting-tube,

in combination with suitably-perforated removable cap, and a deflector, V-shaped in cross-section and located centrally above said jet-orifices, substantially as set forth.

5 2. In a vapor-burner, the valve E, having two jet-orifices, *a a*, controlled by one screw-valve and adapted to discharge through one conducting tube, in combination with perforated cap F and the deflector *b*, substantially as shown and described.

3. In a vapor-burner, the elongated cup B, generator A, and the removable cap F, corresponding in shape to the cup, and provided with an inverted transverse bar, V-shaped in cross-section and located at right angles to the posi-

tion of the jets *a a*, for the purpose of dividing the flame and throwing it to the two extremities of the burner, substantially as specified and shown.

4. In a vapor-burner, the combination, with 20 the cup B and generator A, as shown, of the double-jet valve E and removable cap F, having three or more rows of perforations, and a transverse bar, V-shaped in cross-section, all arranged to operate substantially as and for 25 the purpose specified.

T. TRASK WOODWARD.
